Application December 24, 1942, Serial No. 469,990

10 Claims. (Cl. 81—49)

The present invention relates to tools of the character having pivoted crossed handles and more particularly to a device combined with an ordinary pair of pliers for transforming the pliers into a tool which can grip an object and be locked in gripping position.

Some of the objects of the present invention are: to provide an improved tool for gripping purposes; to provide an attachment for a pair of pliers to increase the effectiveness of the grip thereof; to provide an attachment for pliers wherein the usual operation of the pliers can be carried out in a normal manner; to provide means in combination with a pair of pliers to prevent spreading of the handles once the jaws have taken a grip on an article; to provide a device for use with a pair of pliers wherein provision is made for holding an initial grip on an object and thereafter causing a locking action to function to maintain such initial grip; to provide a combined pair of pliers and device whereby the pliers can function to establish initial grip or bite, and thereafter the device can function to increase the initial grip or bite and finally to lock the pliers in the gripping position; and to provide other improvements as will hereinafter appear.

In the accompanying drawings, Fig. 1 represents a side elevation of a pair of pliers equipped with one form of the present invention; Fig. 2 represents a plan of the same; Fig. 3 represents a detail showing the initial gripping position of the parts; Fig. 4 represents a detail showing the locking position of the parts; Fig. 5 represents a detail of the mounting of the control lever, such detail being from the side opposite to that of Fig. 1; Fig. 6 represents the detail of Fig. 5, with the control member in locking position; Fig. 7 represents a side elevation of a modified form of the invention; Fig. 8 represents a detail in side elevation of the modified form showing the plier handle and holding means in the initial gripping position; Fig. 9 represents the same showing the handles flexed under the influence of the controlling means in locked position; Fig. 10 represents a section on line 10—10 of Fig. 9; Fig. 11 represents a side elevation of another form of the invention, showing the parts ready to grip an object; Fig. 12 represents the same in locked gripping position; Fig. 13 represents a detail in side elevation from the side opposite to Fig. 11, and showing the parts in initial gripping position; and Fig. 14 represents the detail of Fig. 13 with the parts in locked gripping position.

Referring to the drawings, one form of the present invention is shown as applied to the crossed handles 10 and 11 of a pair of pliers, said handles being pivoted at 12, and terminating respectively in the usual clamping jaws 13 and 14.

In order to hold the jaws in a set gripping position, this form of the invention employs a de-

tent 15 fixed to the handle 10 at such a distance from the end thereof as will leave sufficient space for the hand of the user to obtain a good grip thereon. A latch 16 having teeth 17 is suspended by a pivot 18 from the handle 11, and the relation between the pivot 18 and the detent 15 is such that in all operative positions of the handles the detent 15 automatically engages one of the latch teeth 17. As shown, the pivot end of the latch 16 is offset so that the latch can be swung to an inoperative position alongside of the grip end of the handle 11, while the contour of the latch is, preferably, such as to conform to this handle grip part. Thus, when the latch is not in use it lies inconspicuously beside the handle 11 and cannot interfere with the usual operation of the pliers. The latch 16 has a short arm 20 passing transverse of the handle 11 where it is engaged by the free end of a flat spring 21, which is fast to the outer face of the handle 11. The opposite side of this arm 20 is formed with a groove 22 to receive the shaped free end of a second flat spring 23 located in juxtaposed aligned relation to the spring 21. By this construction, the spring 21 acts upon the arm 20 to press the latch 16 towards the detent 15. This spring action takes effect after thumb piece 28 has been pulled back sufficiently far to have moved arm 20 along spring 21 to a position below the center of free end of spring 21. Before arm 20 reaches this position, the action of spring 21 tends to hold arm 20 in a forward position, thereby forcing latch 16 up to and along side handle 11, while the spring 23 acts upon the arm 20 to hold the lever 26, to be described, in its inoperative position. Spring 23 thus tends to hold latch 16, but due to the fact that spring 23 is of lesser holding strength than spring 21, the forward push of the operator's thumb on latch 26 will allow spring 23 to disengage from groove 22 of arm 20, while the greater holding strength of spring 21 will continue to hold teeth 17 in latch 16 against detent 15. In moving to this latter position, the arm 20 deflects the spring 23 so that its end snaps into the groove 22. A stop lug 24 projects from the latch 16 to engage the inner face of the handle 11 and thus, not only limits the travel of the latch 16 but properly locates it beside the arm when it is not in use. The pivot 18 traverses a yoke 25 formed as part of a lever 26, which is pivoted to the handle 11 and which also mounts the spring 23, for coaction with the arm 20. From the foregoing, it will be evident that, when the latch 16 is in operative position, the closing of the plier jaws upon an object will cause the latch teeth to ride over the detent 15 until a grip is established upon the object, whereupon the proper holding tooth of the latch 16 will be pressed into position back of the detent 15 by the action of the spring 21, and thus retain an initial grip.

For the purpose of increasing the bite of the initial grip upon the object and resulting in a positive locking of the pliers upon the object so that the hand of the user can be safely released, the lever 26 is mounted on a pivot pin 27 which traverses the yoke 25 parallel to the pivot 18 and between that pivot 18 and the handle 11. The construction is such that when the lever 26 is swung outwardly to its limit position the latch pivot 18 will be at one side of the vertical plane of the pivot pin 27, while when the lever 26 is swung substantially parallel and in close proximity to the handle 11, then the latch pivot 18 will be at the other side of the vertical plane of the pivot pin 27. The transition from one location to the other occurs with a snap action as the pivot 18 passes dead center in either direction of movement. When the lever 26 is in inoperative position, that is substantially at right angles to the handle 11, the pivot 18 is in one limit position relatively close to the handle 11, but when the lever 26 is shifted to operative position, that is substantially parallel to the handle 11, the pivot 18 is in the other limit position and thus spaced an appreciable distance from the handle 11. This radial increase serves to pull the latch 16 toward the handle 11, and therefore when the detent 15 is engaging a latch tooth to maintain an initial bite the increment of movement of the latch, due to the action of the lever 26, so increases the pressure upon the detent 15 as to form a positive lock upon the object held by the pliers. When so locked the hands of the user can be entirely removed from the pliers without the object being released.

For convenience in use the lever 26 is mounted to swing towards the jaw end of the pliers and has a position such that it can be readily moved by a forward push of the thumb of the user. To facilitate the retracting or interlocking movement of the lever 26, a thumb piece 28 is formed on or otherwise attached to the lever 26 in a convenient place to be engaged by the thumb on the hand which is manipulating the pliers.

The operation of the pliers with this form of the invention is as follows: If the pliers are to be used in the ordinary manner of pliers without such a locking attachment, both the lever 26 and the latch 16 lie unobtrusively along the handle 11 and do not in any way interfere with an effective hand grip or the proper use of the pliers. When, however, the locking action of the attachment is required, the thumb piece 28 is pulled back, raising lever 26 to operating position, and at the same time bearing against the end of lever 16, thus forcing the latter also into operating position against detent 15, where the spring 21 holds it while permitting the necessary flexing action to allow the detent 15 to ride over the teeth as the plier handles are drawn together. The jaws 13 and 14 are now straddled about the object to be gripped and the handles 10 and 11 drawn together in the ordinary manner until the jaws grip the object. The hand grip is applied to so flex the handles that the detent 15 seats back of the then adjacent latch tooth and thus gives an initial firm grip on the object. This grip can now be increased by pressing the lever 26 to its lower position close to the handle whereupon the pivot 18 swings to the jaw side of the pivot pin 27 and thereby increases the pull of the latch so that the handles are subjected to a further flexing and the bite upon the object still further increased. In the swinging of the lever 26, the pivot 18 passes the dead center

with respect to the pivot pin 27 and the third point of load stress, the point of contact between a selected tooth of teeth 17 and detent 15, so that the resilience of the flexed handles causes the lever 26 to be held in locking position. Thus, a complete positive locking position of all of the parts is made possible. To make clear these gripping actions, reference is had to the drawings where in Fig. 3 the dotted lines A represent the position of the handle 10 before the initial grip is established as shown in full line position B. In Fig. 4 the dotted lines represent the initial gripping position B, corresponding to position B of Fig. 3, while the full lines C, show the final flexing which creates the increased grip of the plier jaws on the object and the lock upon the object.

In the form of the invention shown in Figs. 7 to 10, a latch 30 is mounted to swing about a pivot 31 which passes transversely of the channelled sides of a lever 32 pivoted at 33 to the end portion of a plier handle 34. A spring 35 is coiled about the pivot 31 and has one end fixed to the lever 32 and the other end bearing against a lug 36 which projects from the latch 30 to traverse an arcuate slot 37 in the side of the lever 32. This slot 37 has the pivot 31 as a center to allow the latch 30 to swing to a position in close proximity to the handle 34, when not in use. The relation of the two pivots 31 and 33 is the same as described for the preferred form of the invention shown in Figs. 1 and 6, namely the latch pivot 31 operates on a radius from the pivot 33 and can snap past the dead center point to increase the gripping action of the latch and thus form a positive lock. The tension of the spring 35 constantly acts to swing the latch 30 towards the inner side of the handle 34. The latch 30 is of channel shape and of a length to intercept the end of the other handle 38 when moved to its operative position. Also, it is curved on an arc having the pivot 40 of the pliers as a center and therefore when the handles 34 and 38 are brought towards each other, the end of the handle 38 rides along the inner face of the latch. For interlocking purposes, this inner face is formed with a plurality of closely spaced stops 41, which, as shown, are struck inwardly from the material of the latch. Thus, there are a succession of stops 41, one of which is automatically selected by the handle 38 when it moves to an initial gripping position to prevent spreading of the handles and the consequent release of the object held by the pliers.

With this form of invention the operation is as follows: With the handles 34 illustratively substantially horizontal, lever 32 is raised to a substantially vertical position, in which it is resiliently retained by the engagement of the end of handle 34 in the bend 29 in the free end of spring 42. Latch 30 is resiliently urged against the end of handle 38 by coil spring 35, as shown in Fig. 8. With the jaws juxtaposed to an object to be gripped, the handles are relatively moved toward each other by hand in the usual gripping action, causing the end of handle 38 to pass successively over the series of stops 41 until resistance to gripping increases to a point at which the jaws attain an initial grip on the object as the end of handle 38 engages in the appropriate stop 41. The lever 32 is then swung down to parallelism with the handle 34 during which movement the pivot 31 moves upwardly in an arc about pivot 33 to a point just past dead center, in which relative position of the pivots the lever 32 is automatically locked as shown in Fig. 9. When not

in operation, lever 32 is resiliently held against handle 34 by the imposition of a flat portion of spring 42 against the end of handle 34, and latch 30 is held against handle 34 by coil spring 35, as shown in Fig. 7.

In the form of the invention shown in Figs. 11 to 14, one plier handle 45 is provided with a channelled end 46 to receive a pivot pin 47, which mounts an arc shaped latch 48. The inner face of the latch 48 is provided with a plurality of parallel, closely spaced transverse stops 50 formed, as shown, by a succession of slots struck out of the material of the latch. The length of the latch 48 is such as to overlie the end of the other plier handle 51, in all gripping positions of such handle, where it contacts a detent 52 projecting from a lever 53, in order to form an interlock with any one of the stops 50. A coil spring 54 is stretched between the handle 45 and the latch 48 in order to hold the latch 48 against the detent 52. Also this spring 54 facilitates holding the latch 48 beside the handle 45 when the pliers are to be used without operating the locking attachment. The lever 53 is of channel shape to straddle the handle and is shaped to follow the contour of the handle 51 so that when folded against the handle it is unobtrusive and does not interfere with the usual operation of the pliers. As shown, the lever 53 is mounted upon two aligned pivots 55 respectively carried by two lugs 56 fastened to and projecting inwardly of the handle 51. A flat spring 57 is journalled at one end about a pin 58 which traverses the sides of the handle 51. From the pin 58 the spring 57 passes beneath a fixed pin 60 and terminates in an offset end portion bearing against the handle 51. Preferably the pin 58 seats in a groove 61 formed in the spring 57 to limit the outward swing of the lever 53 while allowing the spring to slide along the handle when the lever is swung to its inner position alongside the handle 51. By reason of the eccentric travel of the detent in following the movement of the lever 53 about the pivot 55, a supplemental outward pull upon the latch 48 is exerted after the plier jaws have obtained an initial grip upon an object. Thus when the lever 53 is swung down against the handle 51, the supplemental pull transmitted by the shifting of the detent to a new position causes the latch 48 to be drawn tighter and so flex the handles to create such an increased pressure between the detent 52 and the latch 48 to lock the parts together, after the point of contact between the detent 52 and the particular stop on latch 48 then in use has passed dead center in relation to pivots 55 and 47. When so adjusted, the hand of the user can be released while the pliers remain gripping the object.

It will now be apparent that a novel plier combination has been devised wherein in all forms of the invention illustrated there is provision for holding the initial grip of the pliers upon an object, which holding action may be supplemented by a device to increase this initial grip and lock the holding means. This locking feature operates through an ingenious shifting of a part about a pivot in such a way that the part passes a dead center and can thus create a positive pull upon the plier handles in a direction to prevent spreading thereof. The action of this pull is to cause the handle to flex sufficiently so that the holding detent is held under pressure in the selected latch stop.

Having thus described my invention, I claim:

1. In combination, a pair of pliers having a

pair of pivotally connected handles, gripping jaws respectively on said handles, said handles having a length to be grasped for manual operation of said jaws, a latch pivotally carried by one handle adjacent the end thereof and of a length to engage a part of the second handle, a plurality of stops on said latch for engagement by said part, spring means normally pressing said latch towards said part to bring a stop into latching engagement with said part to hold said jaws in gripping position, and supplemental handle-contracting means associated with said latch and operable after the initial jaw gripping to increase the tension of and to lock said latch to retain said jaws in gripped position upon an object.

2. The combination of a pair of pliers having pivotally connected handles and object gripping jaws, with means for holding said handles in position to cause said jaws to initially grip an object, and means coacting with said holding means to increase the grip upon said object, said coacting means including two pivots, one pivot movable with said means from one side to the other side of the second pivot, said second pivot being mounted on one of said handles.

3. The combination of a pair of pliers having pivotally connected handles and object gripping jaws, with means spanning said handles for holding said handles in an initial contracted relation after said jaws have gripped an object, and means including a pivot shiftable from one side of a dead center to the other side for controlling said holding means to vary said contracted relation whereby the grip of said jaws on an object is increased, said pivot disposed on the spanning means adjacent to a handle.

4. The combination of a pair of pliers having pivotally connected handles and object gripping jaws, with means spanning said handles for holding said handles in an initial contracted relation after said jaws have gripped an object, and a controlling means having a plurality of positions for acting upon said holding means, said controlling means including a fixed pivot on a handle and a movable pivot, said movable pivot being at one side of said fixed pivot and arranged to increase the gripping action of said jaws as it moves from one side to the other side of said fixed pivot and to lock said jaws in gripping position.

5. The combination of a pair of pliers having pivotally connected handles and object gripping jaws, a latch pivotally mounted on one handle, means on the other handle for engagement by said latch to limit the separation of said handles, a lever having a pivot on one handle, means associated with one of the handles and including a second pivot swingable from one side of said lever pivot to the other for increasing the tension on said latch and locking said latch in gripping position of said jaws.

6. In combination, a pair of pliers having a pair of pivotally connected handles, gripping jaws respectively on said handles, said handles having a length to be grasped for manual operation of said jaws, a latch pivotally carried by one handle and of a length to engage a part of the second handle, a plurality of stops on said latch for engagement by said part, spring means normally pressing said latch towards said part, and manually operable supplemental handle-contracting means pivotally mounted on a handle and engaging said latch and operable after an initial gripping of said jaws to increase the tension of

and lock said latch to retain said jaws in gripped position.

7. A gripping tool comprising a pair of relatively movable handles, jaws operatively associated with said handles and arranged to move toward gripping engagement with an article as the handles move relatively together under manual manipulations, tensioning latch means effectively carried by one handle and movable to extend from one handle to the other, said latch means having an operative coupling with one handle and another operative coupling with the other of said handles, the first mentioned coupling comprising a lever pivoted to its associated handle and having substantially arcuate stop-limited motion between a first and a second position, said lever having a pivotal connection with the tensioning latch means disposed on one side of the lever pivot longitudinally of the handle carrying the lever and in a given spaced relation to said handle in said first position of the lever, which pivotal connection is movable with the lever to a position on the other side of the lever pivot longitudinally of the lever carrying handle and in greater spaced relation to the said handle in the second position of the lever, said latch means and operative couplings so arranged that with the lever in the first position and an initial manual tensioning of the handles being first applied an initial longitudinal tension is then applied to the tensioning latch means to maintain substantially a given initial grip on the jaws, said operative couplings and tension latch means being further so arranged as to increase the tension on the latch means to increase the tensioning of the handles in swinging the lever to and to urge it to remain in its second position and so as to lock the tool in a second gripping engagement.

8. A gripping tool comprising a pair of relatively movable handles, jaws operatively associated with the handles arranged for gripping movement as the handles move relatively together, tensioning latch means effectively carried by one handle and movable to extend from one handle to the other, an operative coupling associating and anchoring the tensioning means with one handle, another operative coupling associating and temporarily anchoring the latch means with the other handle, a selected one of said couplings comprising a lever pivoted on its associated handle and having a substantially arcuate stop-limited motion between a first and a second position, said selected coupling further comprising a pivotal connection between the lever and tensioning latch means with the connection in the first position of the lever disposed on one side of the lever pivot longitudinally of its associated handle and in a given spaced relation to said handle and with the tensioning latch device under an initial tension arising from the manual tensioning of the handles in an initial gripping actuation thereof, said pivotal connection in the second position of the lever being disposed on the other side of the lever pivot longitudinally of the same associated handle from its said first disposition and in greater spaced relation to the said handle so that in swinging the lever from its first to its second positions there is developed and maintained an increased tension on the tensioning latch means to enhance the tensioning of the handles to increase the gripping action of the jaws which also urges the lever to remain in its second position by requiring in-

crease of tension of the tensioning latch means in returning to the first lever position so as to lock the tool in its increased gripping engagement of the jaws.

9. A gripping tool comprising a pair of relatively movable handles, gripping jaws operable thereby, a lever pivoted to one handle and movable between a first and a second position thereon, said lever-carrying handle having a stop surface abutted by the lever in its said second position, a tensioning latch device, means for pivotally connecting the tensioning latch device to the lever eccentric to the lever pivot, means for pivotally connecting the tensioning latch device to the other handle opposite to the one having the lever, the first mentioned pivotal connection being at one side of the lever pivot longitudinally of the associated handle in the first lever position with the handles in a given spaced relation incidental to an initial gripping engagement of the jaws, said first mentioned pivotal connection moving with the lever to a position on the other side of the lever pivot longitudinally of the handle carrying the lever with the handles in a second spaced relation incidental to a secondary enhanced gripping engagement of the jaws with the lever in its said second position, the secondary enhanced gripping engagement of the jaws being accompanied by increased tension on the tensioning latch device by which the lever is forced against said stop surface from which it can only be dislodged pursuant to a momentary increase in tension of the tensioning device between the handles and thus locks the lever and thus the gripping tool in a gripping relation.

10. A gripping tool comprising a pair of relatively movable handles, jaws operatively associated with the handles arranged for gripping movement as the handles move relatively together, tensioning latch means effectively carried by one handle and movable to extend from one handle to the other, an operative coupling associating the tensioning latch means with one handle, another operative coupling associating the tensioning means with the other handle, the respective couplings being arranged to anchor the tensioning means and handles together with variable clearance between handles, said first mentioned coupling comprising a lever pivoted on its associated handle and having a substantially arcuate stop-limited motion between a first and a second position, said first mentioned coupling further comprising a pivotal connection between the lever and tensioning means with the connection in the first position of the lever disposed on one side of the lever pivot longitudinally of its associated handle and in a given spaced relation from said handle and with the tensioning latch device under an initial tension arising from the manual tensioning of the handles in an initial gripping actuation thereof, said pivotal connection in the second position of the lever being disposed on the other side of the lever pivot longitudinally of said associated handle from its said first disposition in greater spaced relation to the said handle to develop and maintain an increased tension on the tensioning latch means to enhance the tensioning of the handles to increase the gripping action and to urge the lever to remain in its said second position after swinging from its first to its second position relative to its associated handle so as to lock the tool in said second gripping engagement.

STANLEY R. BOCCINO.
